CLAIM

The ornamental design for a combined toothbrush and refillable-type dental floss holder, as shown and described.

DESCRIPTION

FIG. 1 is a top perspective view of a combined toothbrush and refillable type dental floss holder showing my new design;

FIG. 2 is a left side elevational view thereof, the right side being a mirror image;

FIG. 3 is a top plan view thereof;

FIG. 4 is a bottom plan view thereof;

FIG. 5 is a rear end elevational view thereof; and

FIG. 6 is a fragmentary perspective view of a second embodiment of the design in FIG. 1 wherein the only difference resides in the shape of the dental floss holder, that shape being a sphere.

FIG. 6
